DEVICE FOR KEEPING OUTBURSTS OF FIRE
IN FILM PROJECTORS UNDER LOCAL CON-
TROL

Josef Plachmann, Cologne, Germany

Application March 17, 1934, Serial No. 716,012
In Germany March 21, 1933

6 Claims. (Cl. 88—17)

To prevent the fire of blazing films—which happens more especially at times, when the film stops motionless in front of the projecting gate—from spreading to the interior of the drums which contain the coils of film, equipment has been provided at film drum entrance and film drum exit which, by means of cutting devices, sever the blazing film portion between the drums from the film coils within the drums, and at the same time, effect the closing of the drum outlets. In this way the rotating film coil carriers are prevented from drawing burning or smouldering film portions into the drums. Known devices have been equipped for this purpose with cutters which are operated by spring action or electro-magnets. These cutters are released by means sensitive to temperature, for example highly inflammable strips of film, which are arranged in the vicinity of the projecting gate and which in their turn are set afire by the blazing film. These film strips have been arranged in the shape of a long thread slung around the projecting gate, whilst its ends were taken to the cutting devices which are kept in the "stand-by" position by means of tension of the undamaged thread.

Devices are also known which automatically shut the projecting aperture in film operator cabins comprising a strip of highly inflammable film arranged in close proximity of the projecting gate and a spring operated switch which is fixed somewhere to the side frame of the projecting machine and kept in "off" or "no current" position by means of the undamaged thread and the tension of a cord attached thereto. The destruction of the film thread which controls the operating of the device causes the tension of the cord to relax, the switch operates by released spring action and closes a circuit of electric current connected to the safety devices.

All these known devices, however, are by no means free from considerable drawbacks. For operating they rely on inflammable threads or cords attached to inflammable threads which are connected to cutting devices or a switch some considerable distance away. It is obvious that thereby the danger of damage to or the destruction of the thread or intermediate cord is increased and the possibility of needless operating of the safety devices presents itself. Needless action of safety devices, however, causes most undesirable interference with the operating of the projecting machine. Suitable covering up of the openly stretched inflammable thread or cord cannot avoid these disadvantages, as, in the first instance, covering up means the addition of con-

structional parts to the projecting machine, more important, however, is the fact that the stretch of cord or thread is withdrawn from indispensable observation, thus preventing the detection in time of circumstances and interferences which hamper prompt action of the safety devices. Further disadvantages appear in the course of operating the film projecting machine. It is obvious and seems to the purpose to fix the inflammable strip or thread of film operating the safety devices to the shutter of the projecting gate. The operating of the film projecting machine necessitates frequent opening and shutting of this gate, whereby the tension of thread or strip relaxes or tightens resulting in needless operating of the safety devices. Thus the known devices are bound to cause frequent stoppages in the running of the film projecting machine. And, finally, the necessary replacement of the inflammable threads or cords, after destruction of temperature-sensitive means causes considerable loss of time, for utmost care is required for correct adjustment to prevent the switch or cutting devices from being released under ordinary running conditions of the film projecting machine.

Disadvantages of the aforementioned description are absent with the device which the present invention has for object. It relates to a device for keeping outbursts of fire in film projecting machines under local control and comprises the control of cutting devices fixed in the vicinity of the film drums and means sensitive to temperature arranged in close proximity of the projecting gate of the machine. The means sensitive to temperature and the devices controlled by their influence are, in accordance with the nature of this present invention, arranged on a locally restricted area in the vicinity of the film band and projecting gate, on the gate shutter itself by preference, under abolition of all and any mechanical means for the transmission of forces or impulses released under the influence of these heat-affected means.

The present new device dispenses with all mechanical power transmissions, as the force or impulse released by the heat-affected means is transmitted by electric currents, thus, there are only electric wires leading away from the film projecting gate, and, as these do not transmit any mechanical forces, they can be conducted in such a manner as to avoid their damaging or destruction and consequent needless operating of the safety devices is reliably excluded.

This novel device comprises contacts to open 55

or close electric circuits which former are mounted on double armed levers pivoted on a common shaft or pin. The ends of a lever pair on one side of the pivot carry a strip of highly inflammable material under tension, whilst the lever ends on the other side of the pivot have contacts mounted thereon which, after destruction of the inflammable material and under the influence of spring action or their own gravity, close an electric circuit. The inflammable strips consisting of film band are suitably arranged close to the projected film immediately above and below the projecting gate of the machine.

The cutting devices are suitably arranged in closest proximity of the safety channel mounted on each film drum.

The accompanying drawing shows by way of example how the present invention may be performed.

20 Fig. 1 shows a sectional view of the projecting gate of a film projector over the line I—I of Fig. 2 and a similar view of the film coil carrying lower drum housing with safety channel and the cutting devices arranged laterally thereof;

25 Fig. 2 shows a front view of the projecting gate with devices operated by the burning film and releasing thereby the aforementioned cutting devices;

30 Fig. 3 shows a sectional view of Fig. 2 over the line III—III;

Fig. 4 shows a sectional view of Fig. 1 over the line IV—IV;

35 Fig. 5 is a side view of a projecting machine showing the disposition of the cutting devices and the arrangement near the projecting gate of means sensitive to temperature.

In Figs. 1—5 1 is the projecting gate of a film projecting machine, 2 the picture film, 3 a drum housing for the reception of the picture film, 40 4 and 5 are guide rolls arranged in front of guide channel 6 comprising principally a channel of rectangular section through which the picture film is drawn.

45 The device for cutting the picture film comprises a supporting frame 7 mounted on drum housing 3. Twin tubular guides or guide cylinders 8 are fixed to this frame 7. Within bores 8 of guide cylinders 9 piston-shaped cutter holders 10 are slidably arranged. These holders 10 have slots 11 for the reception of cutter 12 which severs the picture film 2. The cutter holders 10 are under the influence of spiral springs 31 arranged between the cutter holders and supporting frame 7. These springs 31 have the tendency of forcing the cutter in the direction of the picture film. The cutter is guided in slots 34 of guide cylinders 9 and further guides 36. Cutter holders 10 are retained in "stand by" position by means of catches 14 provided at the ends of double armed levers 15. Catches 14 pass through apertures 32 of guide cylinders 9 and engage with grooves 33 provided for that purpose in cutter holders 10. Both catches are kept in that position by the pull of spiral springs 13 fixed to the opposite ends of levers 15. Double armed levers 15 are equipped with cross piece 35 which in its turn carries a small pure iron contact plate 30. Magnet coil 24 is fixed to supporting frame 7. The iron core 26 of said coil opposes contact plate 30 with a very narrow space between both.

70 The devices effecting the release of the cutting devices are arranged, by preference, on the projecting gate shutter or picture window gate 40, in a manner which holds the strips of inflammable material to be destroyed by the blazing

picture film immediately above and below the projecting gate in a very close position to the picture film. The opening in the picture window gate frame is as shown much larger than the opening in the projecting gate and hence the strips of inflammable material may be within the former opening and yet not obscure the projecting opening of the gate. Each one of these devices comprises two double armed levers 16 and 17, pivoted at 18 and under the influence of spring 19. This spring 19 has the tendency of forcing the opposite ends of said levers toward one another so as to cause the insulated contacts 20 and 21 mounted on these lever ends to touch one another. This movement is prevented and the "stand by" position of the contacts is maintained by a strip of highly inflammable material 22, preferably of unexposed film, slung around the opposite ends 16 and 17 so as to form an endless band. Contacts 20 and 21 belong to electric circuits shown in Fig. 5 which comprise coils 24 beside a current source or supply. Contacts 20 and 21 are connected to these circuits by means of contact screws 25.

Fig. 5 shows that a device as illustrated by Figs. 1—4 is provided for each film drum. It will further be seen that safety devices are arranged above and below the projecting gate of the machine respectively to operate the cutting devices.

The working of the contrivances as illustrated on the drawing is effected in the following manner: in the case of the picture film catching fire in front of the film projecting gate, the fire spreads simultaneously to bands 22. The immediate destruction of these strips causes the release of the lever ends in proximity of the film projecting gate and, under the influence of springs 19, the lever ends which carry contacts 20 and 21 are forced towards each other until said contacts touch and thereby close an electric circuit conducted over coils 24 and a current source. Iron core 26 becomes magnetic and contact plate 30 on cross piece 35 connecting levers 15 is drawn towards said coil. Catch 14 becomes by this action disengaged from grooves 33 in the cutter holders. The cutter jumps forward under the pressure of springs 31 and severs the picture film. A lead plate 28 disposed laterally of the safety channel serves as stop for the cutter motion. As strip 22 is destroyed very quickly, or at least relaxes its tension in extraordinarily short time and, as the cutting devices are released by electric action, the severing of the picture film portion between the film drums is effected with extraordinary speed. The coils 24 are in serial connection ensuring simultaneous operating of both cutting devices. The circuits are arranged in such a manner that, as the diagram in Fig. 5 clearly shows, both cutting devices operate simultaneously, even when but one of the inflammable strips has been destroyed.

This novel device for keeping the fire of burning picture films locally controlled is re-set or returned to the "stand by" position in the most simple manner by bringing the band carrying ends of the levers nearer to one another and fixing a new strip or band of inflammable material, a measure which is executed within a few seconds. Thereafter, the released cutters are drawn back by means of handles 27 fixed to them, until catches 14 re-engage with grooves 33 of the cutter holders.

The new device is easily adapted to the various types of film projecting machines, more especially to the different disposition and size of the

projecting gate shutter or projecting gate proper. In most cases it will suffice to alter the position of pivot 18 and modify the shape and length of the levers in order to ensure the inflammable strip of material always being held in close proximity of the picture film immediately above or below the film projecting gate respectively.

Further, the cutting devices may be operated either over "working current" circuits or else over "no current" circuits; in the former case a circuit is closed by the heat controlled switch, in the latter case it is interrupted.

Further, the safety devices may also be worked by hand-operated switches, preferably push-buttons, in order to release the cutting devices by hand, should for some reason or other the heat controlled switches fail to work.

Having now described in detail the nature of this present invention and shown by way of example and accompanying drawing the manner in which it may be performed.

I claim:—

1. Safety device for confining outbursts of fire in film projecting machines, comprising in combination a casing having projecting openings therein, a picture window gate, the picture window of which is larger than the projecting opening of the casing and directly behind the same, electromagnetically operated cutting devices for the film in front of and behind the burning portion thereof, ignition means adapted to be inflamed from the burning film, electric switches being automatically operated when the said ignition means are inflamed said burning switches being arranged in a circuit wherein the electromagnets of the cutting devices are arranged and said ignition means arranged in that part of said picture window which does not register with the projecting opening of the casing and immediately adjacent the film moving past the picture window.

2. Safety device according to claim 1, the said

cutting devices for the film being arranged directly in front of the opening of each film drum.

3. Safety device according to claim 1, the said ignition switches being arranged on the picture window gate itself.

4. Safety device according to claim 1, the said burning switches consisting of double-armed levers rotatable on a common axis, the arms of said levers being designed as electric contacts on the side turned away from the gate frame, the arms of said levers turned toward the gate frame being bent into the opening of the frame and adapted to receive the ignition means, springs adapted to bring the said levers against forces of pressure or tension exerted by unburnt ignition means into the position in which they close the circuit, the electromagnets of the cutting devices being arranged in the said circuit.

5. Safety device according to claim 1, the said ignition means consisting of film material and the picture window gate is adapted to permit a film wound on both drums to be inserted in or removed from the projector.

6. Safety device for confining outbursts of fire in film projecting machines, comprising in combination, a casing having a projection opening therein, a picture window gate the picture window of which is larger than the projecting opening of the casing and directly behind the same, cutting devices for the film above the projection window opening and below the projection window opening, ignition means adapted to be inflamed from the burning film, the said cutting devices being automatically operated on the destruction of continuity of said ignition means and the said ignition means being arranged in that part of said picture window which does not register with the projecting opening of the casing and immediately adjacent the film moving past the picture window.

JOSEF PLACHMANN.
